UNITED STATES PATENT OFFICE.

JOSEPH D. BAGLEY, OF SPRINGVILLE, UTAH.

METHOD OF TREATING PHOTOGRAPHIC DRY PLATES OR FILMS.

1,417,791.

Specification of Letters Patent. Patented May 30, 1922.

No Drawing.

Application filed February 7, 1921. Serial No. 443,311.

To all whom it may concern:

Be it known that I, JOSEPH D. BAGLEY, a citizen of the United States, residing at Springville, in the county of Utah and State 5 of Utah, have invented certain new and useful Improvements in Methods of Treating Photographic Dry Plates or Films; and I do declare the following to be a full, clear, and exact description of the invention, such 10 as will enable others skilled in the art to which it appertains to make and use the same.

This invention relates to an improved method of treating photographic dry plates 15 or films.

One object of the invention is to greatly increase the degree of clearness in the pictures produced from the negatives, especially where cloud effects are being reproduced.

20 A further object is to attain the above object by a very simple, easy and comparatively inexpensive operation.

Other objects and advantages may become 25 apparent to persons who read the following details of description and appended claim.

My invention consists in utilizing alcohol, unmixed with other ingredients; in the development of photographic dry plates or films, and it has been found by experiment 30 that when negatives are produced on such dry plates, their quality is greatly improved by applying alcohol to the sensitized surface prior to subjecting them to the action of the ordinary developing liquid or composition. 35 In other words, I employ old and well known materials, but I treat them by the following new method:—

I take the ordinary plate or film which has been previously treated with a single or 40 double coat of sensitizing material, make the

exposure so as to produce an image on the sensitized surface, then immerse the plates or film in pure alcohol for thirty minutes or more, that is, for such a period that each and all pores in the gelatine emulsion, with 45 which the plate or film is coated, are entirely filled with alcohol; after which the plate or film may be placed in any ordinary developer and thereby developed in the usual way. By pure alcohol I mean pure grain alcohol, 50 since denatured alcohol will not serve the purpose of this invention.

The operator must not place the plate or film in water after being immersed in the alcohol, as this will cause the plate or film 55 to develop unevenly. After the plate or film has been removed from the alcohol bath, the ordinary developer is applied in the ordinary way, and upon printing from a negative developed in this way, it is found that 60 where clouds, water, land and other contrasting objects are photographed, they are all clearly distinguished from one another in the finished photograph.

Having fully described my improved 65 method, what I claim as my invention is:

The method of treating photographic dry plates or films consisting in subjecting the dry plates or films to the action of alcohol after exposure and before development and 70 while wet with alcohol subjecting them to the action of a photographic developer.

In testimony whereof I have hereunto set my hand in the presence of two subscribing witnesses.

JOSEPH D. BAGLEY.

Witnesses:

D. C. JOHNSON,
ELFIE HUNTINGTON.
